UNITED STATES PATENT OFFICE.

WILLIAM M. RYAN, OF PULLMAN, ILLINOIS.

DUST-GUARD.

SPECIFICATION forming part of Letters Patent No. 742,907, dated November 3, 1903.

Application filed December 24, 1901. Serial No. 87,127. (No model.)

To all whom it may concern:

Be it known that I, WILLIAM M. RYAN, a citizen of the United States, residing at Pullman, Cook county, Illinois, have invented 5 certain new and useful Improvements in Dust-Guards, (Case No. 2,) of which the following, taken in connection with the accompanying drawings, is a specification.

This invention has reference to dust-guards 10 such as are employed most commonly on car-journals to protect the same against the entry of dirt or foreign matter which would tend to injure or heat the bearings. It is designed to improve in ease of operation, efficiency, 15 and durability the dust-guard disclosed in my former patent, No. 646,462, of April 3, 1900.

The first of the objects of this invention is the provision of a dust-guard provided with a plurality of segments, one or more of which 20 are constructed of a metal body portion having a relatively soft wearing-surface formed of some substance such as wood or fiber.

Another object of this present invention is the provision of a dust-guard having segments 25 held together by rods and a spring-pressure, with pockets for the same, which are closed against the outside to prevent the entry therein of grease or other foreign matter, such as would interfere with the spring action.

30 The above, as well as such other objects as may hereinafter appear, I attain by means of a construction which I have illustrated in preferred form in the accompanying drawings, in which—

35 Figure 1 is a vertical section showing my improvement applied to a journal-box, such section being taken on the line 1 of Fig. 2. Fig. 2 is a section taken on the line 2 of Fig. 1, showing the parts on a horizontal sectional 40 plane. Fig. 3 is a side elevation of my improved form of dust-guard with the several segments assembled in position. Fig. 4 is a sectional view through the same, showing the relative arrangement of the rods and springs 45 which form the devices for holding the parts together. Fig. 5 is an interior edge elevation of one of the segments. Fig. 6 is a detail section taken on the line 6 of Fig. 4, and Fig. 7 is a view in perspective of an improved form 50 of dust-guard segment forming one part of my invention.

By reference to Figs. 3 and 4 particularly

it will be seen that in carrying out my invention I provide a guard constructed primarily of side pieces 8 and 9, between which I embrace wedge pieces or segments 10 and 11, the whole being secured in position by means of rods 12, held by springs 13, housed in spring-pockets 14, which are closed after the rods and springs are put in place by means of a 6c small plug 15, glued or otherwise securely fastened in the opening to prevent the entry of dirt and the disarrangement of the spring or interference with its action which would be caused thereby. The wedge-segments 10 65 and 11 are made in two parts, as clearly shown in Figs. 6 and 7, the wearing-section 16 being of some soft material—such, for example, as wood or fiber—combined with or fastened to a metal body portion 17, the connection between the two being preferably made by a dovetail joint, as shown at 18 in Fig. 6. The metal part 17 is formed with a slot or opening 19 to accommodate the rod 12 and has its side faces, which engage with the corresponding 70 faces or edges of the side pieces 8 and 9, formed of wedge shape, as heretofore known in the art, so that as the spring pulls upon the rod 12 the side pieces 8 and 9 will be drawn inward, so as to press against the axle, and 75 the wedge-segments 10 and 11 will at the same time be pushed against the axle by the operation of the wedge-surfaces. It will be obvious that the body portions of the wedge-segments used in my present improvement 80 being of metal, there will be a better sliding action of the same upon the side pieces, and consequently a freer action of the guard in following up the wear upon the axle, than is the case where wedge-segments made entirely 85 of wood have been used, as has been the prior practice. Another advantage of my improved combination wedge-segments is that they are less liable to be broken than those made entirely of wood or fiber or like material, since 90 the points of the wedge-segments, which are on account of limited space necessarily rather small, have a tendency in those made of soft material to break off, especially because of 95 having to be provided with the slot 19 for the accommodation of the rod 12. In constructing the part 17 of the wedge-segment of metal 100 this difficulty is entirely obviated.

Having thus described my invention, what

I claim as new, and desire to secure by Letters Patent, is—

1. In a dust-guard the combination of two non-metallic side wearing-pieces, connecting-
5 rods and springs pressing the side pieces together, and wedge-sections between the side pieces, composed of metal heads for bearings on the side pieces and slotted for said rods and having non-metallic wearing-faces there-
10 on, the side pieces being recessed so as to allow of the metallic heads taking the pressure.
2. In a dust-guard the combination of two non-metallic side wearing-pieces, connecting-
15 rods and springs for holding the said pieces together and wedge-sections let into slots in

the sides and composed of metal heads for bearing on the sides, said wedges being slotted for said rods and having non-metallic wearing-faces inserted in said head portions, there being recesses in the side pieces de-
signed to relieve the said non-metallic faces of the wedges of pressure.

In testimony whereof I have hereunto set my hand in the presence of two subscribing witnesses.

WILLIAM M. RYAN.
